(57) **CLAIM**

I claim the ornamental design for a grater, as shown and described.

DESCRIPTION

FIG. 1 is an isometric view of a grater;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The ornamental design which is claimed is shown in solid lines in the drawings. The broken lines in the drawings represent unclaimed boundaries of the design.
